Primary Examiner — Angela J Lee*Assistant Examiner* — Shawn T Gingrich(74) *Attorney, Agent, or Firm* — Michael Best and
 Friedrich LLP(57) **CLAIM**

The ornamental design for a tuner, as shown and described.

DESCRIPTION

FIG. 1 is a rear, top, left perspective view of a tuner showing
 my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The even-dash broken lines illustrating portions of the tuner
 form no part of the claimed design.**1 Claim, 5 Drawing Sheets**(56)
